UNITED STATES PATENT OFFICE

JAMES A. B. LOVETT, OF PITTSBURGH, PENNSYLVANIA, ASSIGNOR TO THE KOPPERS COMPANY, A CORPORATION OF DELAWARE

COKE OVEN APPARATUS

Application filed February 12, 1927. Serial No. 167,611.

My invention relates to coke oven apparatus and it has particular relation to means for preventing the formation of carbon deposits on the interiors thereof.

5 My invention has for one of its objects to provide simple and efficient means for preventing the formation of hard, solid carbon deposits on the roofs and side walls of coke ovens.

10 A further object of my invention is to provide means automatically controlled in accordance with their position in the oven for removing any foreign material that may be deposited on the roofs or walls of coke ovens.

15 In the operation of coke ovens as usually practiced, especially when ovens are charged with fine coal, a hard, solid deposit of carbon forms on the roof and a portion of the side walls thereof above the charge. The deposit is known as "roof carbon". This deposit, if undisturbed, gradually grows in thickness and it is customary to remove as much of it as possible during the allotted empty period of the oven.

20 The process of removal, which is known as "scurfing", requires considerable time and must take place between the operations of pushing and charging the oven. The scurfing time may be varied by increasing or diminishing the number of ovens left empty

25 between the pushing and the charging of any individual oven. In addition, there must be employed apparatus, such, for example, as a steam jet for supplying larger quantities of air through the oven and across the top thereof in an effort to burn the carbon deposit.

In order to avoid the loss of time in operation of the oven and the labor and expense 30 incident to the removal of such deposits, I have found that the deposits may be prevented by removing the materials of which they are composed at intervals sufficiently frequent to prevent carbon formation.

45 Various theories have been advanced as to the cause of carbon deposits in coke ovens, but my investigations have substantiated the facts that such deposits are caused by particles of coal that are blown up against the 50 roof and the side walls during the charging

of the oven. These particles, by reason of the heat of the walls, are softened and caused to adhere to the brickwork above the coal line. In addition, if any air enters the oven as by leakage, imperfect combustion of gases 55 of distillation occurs and lamp-black is formed, which also adheres to the interior surfaces above the charge of coal. If this material is allowed to remain for a period of approximately 24 hours, the volatile matter is driven out of the coal particles and only carbon and a small amount of ash remain. The result is that a hard, solid deposit of carbon is formed on the surfaces of the oven above the charge of coal and this 60 deposit is removed only with difficulty.

In accordance with my invention, I provide the usual pusher ram with air nozzles by means of which blasts of air or other gas may be supplied to the roof of the oven and to such adjacent portions of the side walls as may be desired, while the ram is reciprocating in the oven. The supply of air to the nozzles is automatically controlled by the position of the ram and the nozzles in the 70 oven.

In the accompanying drawings,

Figure 1 is a view, in side elevation, of a pusher machine with my invention applied thereto;

Fig. 2 is a plan view of the apparatus of Fig. 1;

Fig. 3 is a longitudinal sectional view of a portion of a coke oven with a portion of the pusher ram in position therein;

Fig. 4 is a transverse sectional view of the structure of Fig. 3;

Fig. 5 is an end elevational view of the apparatus of Fig. 1;

Fig. 6 is a view, partly in elevation and 90 partially in section, of the mechanism for connecting the movable and the stationary portions of the fluid pressure line; and

Fig. 7 is a diagrammatic view of the automatic means for controlling the fluid pressure line.

Referring to Figs. 1, 2 and 5, a pusher machine 1 that is adapted to operate in connection with a coke-oven battery (not shown) is mounted on rails 2 that are parallel to the 100

battery. The pusher machine 1, which is usually constructed of structural steel, is provided at its top with a pusher ram 3 that extends transversely to the battery. The ram 3, which is provided with the usual head 4, is driven by a mechanism comprising, for example, an electric motor 5 and gear mechanism 6 for connecting the motor 5 to a rack 7 on the ram 3.

A fluid pressure system with which the pusher machine 1 is provided, comprises a compressed air tank 10, a compressor 11, a pipe line 12, extending from the tank 10 to a hose reel 13, flexible hose 14, a pipe 15 that extends along the upper surface of the ram 3 and nozzles 16 that are located adjacent the upper end of the ram head 4. The nozzles 16 are mounted at an angle to the vertical.

Reference may now be had to Fig. 6, in which the details of the connections between the pipe line 12 and the flexible hose 14 are illustrated. The reel 13, upon which the hose 14 is wound, comprises a shaft 18 having a passageway 19 through a portion thereof and which is connected through a lateral opening to the hose 14. The end of the shaft 18, containing the passageway 19, extends into a stuffing box 20 that is connected to the pipe line 12. The stuffing box 20 may be provided with packing of any suitable material, indicated at 21, whereby there is no leakage of air between the rotating shaft 18 and the stationary portions of the stuffing box.

The shaft 18 is mounted in suitable bearings 23 and is provided at the end opposite from the stuffing box with a drum 24, upon which is wound a cable 25 that extends over a pulley 26. At the outer end of the cable 25, weights 27 are suspended for yieldingly maintaining the reel 13 in position with the hose 14 completely wound thereon.

The connections between the tank 10 and the nozzles 16 are controlled by a suitable valve 28 in the pipe line 12. While this valve 28 may be of any suitable or usual character, it has been illustrated in Fig. 7 for convenience as of the globe type and controlled by an electromagnet 29. The circuit of the coil of the electromagnet 29 is controlled by a limit switch mechanism 30 comprising pairs of limit switches 31 and 32 and a cam nut 33 that is actuated by a screw 34, the latter being operatively connected to the driving mechanism of the ram 3 by means of a sprocket-and-chain mechanism 35, whereby the position of the cam nut 33 is dependent upon the position of the ram 3 with respect to the coke oven within which the ram is operating.

It may be assumed that the coke oven 36, a portion of which is illustrated in Figs. 3 and 4, is being pushed and that the ram 3 is adjacent the outer end of the oven on the pusher side. It may be assumed further that there is an accumulation of carbonaceous material 37 on the surfaces above the coke. The switches

31, for example, are closed and the switches 32 are open. When the pusher head 4 is a short distance within the oven, the switches 32 are operated to close the circuit of the electromagnet 29 and the valve 28 is operated to admit compressed air to the pipe line 12 and the other connections to the nozzles 16.

The nozzles 16, which are adjacent to the roof and to the upper portions of the side walls of the oven, apply blasts of air to the adjacent surfaces and effectually blow any soot or particles of coal or loose carbon from the walls. When the ram 3 approaches the end of the oven on the coke side of the battery, the cam nut 33 operates the limit switches 31 to open the circuit of the electromagnet 29 and the valve 30 is closed by a spring 37.

When the ram is reversed and reaches a point corresponding to that at which the supply of air was cut off, the limit switches 31 are again closed and air is supplied to the nozzle 16 throughout the return movement of the ram. When the ram 3 approaches the end of the oven on the pusher side, the switches 32 operate to open the circuit of the electromagnet 29 and the supply of air is again cut off. It will be understood that no air is supplied until the ram 3 is operated in connection with the next oven on the pushing schedule.

During the operation of the ram 3 into the oven 36, the reel 13 rotates to unwind the hose 14 to the extent that is required, the weights 27 being lifted correspondingly. The connections between the pipe line 12 and the hose 14 are maintained airtight during the relative movement of the parts of the stuffing box 20. During the return movement of the ram, the weights 27 operate the reel 13 to rewind the hose 14.

The supply of air in the tank 10 is maintained by the compressor 11, which may be controlled by an arrangement similar to that of the well-known compressors of street-railway cars in which a pressure-controlled switch effects the operation of the compressor when the pressure falls to a minimum value and discontinues the operation of the compressor when the pressure reaches a maximum value and in which the maximum and minimum values may be adjusted as desired. These details are neither illustrated or described since they constitute no part of the present invention.

While I have referred in the specification to roofs and walls of coke ovens, it will be understood that the term "wall", as used in the claims, is used in its generic sense to refer to any of the interior surfaces of coke ovens.

It will be noted that I have provided a structure that may be adapted to existing apparatus and which operates automatically in conjunction therewith to effectually remove initial or incipient deposits on the walls of

coke ovens which would otherwise solidify and be difficult to remove. The removal of the soot or coal in the manner previously described is accomplished simultaneous with the operation of the pusher and there is accordingly no loss of time, as is the case where the carbon deposits are removed as a special operation. In addition, the apparatus required to accomplish the foregoing results is comparatively simple and operates without materially reducing the temperatures of the walls treated thereby.

The employment of my invention materially reduces the travel otherwise required of the pusher machine because of the relatively large number of empty ovens. The number of empty ovens has been reduced and the production of the battery correspondingly increased. No steam jets are required. The life of the standpipes is increased since they are no longer brought to red heat as is the case in scurfing the ovens.

The foregoing and other advantages will be apparent to those skilled in the art relating to coke ovens. It is conceivable that the apparatus embodying my invention may be variously modified and it is understood, therefore, that the scope of my invention is not limited except as indicated in the claims.

30 I claim as my invention:

1. The combination with a coke oven, of means reciprocable therein for applying fluid under pressure to portions of the interior walls thereof.

35 2. The combination with a coke oven, of means reciprocable therein for applying fluid under pressure to portions of the interior thereof, and means for controlling the operation of said fluid-applying means to apply fluid in accordance with its position in said oven.

40 3. The combination with a coke oven and a pusher ram therefor, of means carried by said ram for applying fluid under pressure to portions of the interior walls of said coke oven.

45 4. The combination with a coke oven and a pusher ram therefor, of means carried by said ram for applying fluid under pressure to portions of the interior of said coke oven, and means for automatically controlling the operation of said fluid-applying means to apply fluid in accordance with its position in said coke oven.

50 5. The combination with a coke oven and a pusher ram therefor, of a nozzle on said ram adapted to operate adjacent to a wall of said coke oven and means for supplying fluid under pressure to said nozzle.

55 6. The combination with a coke oven and a pusher ram therefor, of a nozzle on said ram adapted to operate adjacent to a wall of said coke oven and means automatically controlled in accordance with the longitudinal position of said ram relative to said coke

oven for supplying said nozzle with fluid under pressure.

7. The combination with a coke oven and a pusher machine comprising a ram, of a source of fluid pressure carried by said machine, a nozzle carried by said ram and movable adjacent an interior surface of said coke oven, and means for operatively connecting said source to said nozzle.

75 8. The combination with a coke oven and a pusher machine comprising a ram, of a source of fluid pressure carried by said machine, a nozzle carried by said ram and movable adjacent an interior surface of said coke oven, means for connecting said source to said nozzle throughout their relative movements caused by the operation of the ram, and means for regulating the supply of fluid to said nozzle in accordance with the position of said ram and said nozzle relatively to said coke oven.

80 9. The combination with a pusher ram for coke ovens, of a nozzle on said ram and means automatically controlled in accordance with the longitudinal position of said ram relative to said coke ovens for supplying said nozzle with fluid under pressure.

85 10. The combination with a pusher ram for coke ovens and a support therefor on which said ram is mounted for longitudinal movement, of a nozzle on said ram, means comprising a valve for supplying fluid to said nozzle, and means for automatically controlling said valve to open and to close it when said ram is in certain predetermined positions relative to said support.

90 11. The combination with a pusher machine for coke ovens comprising a support and a ram mounted for longitudinal movement thereon, of fluid-pressure apparatus comprising a nozzle carried by said ram and means for automatically supplying fluid to said nozzle when said ram occupies a predetermined portion of its path of longitudinal movement.

95 In testimony whereof, I have hereunto subscribed my name this 11th day of February, 1927.

J. A. B. LOVETT.
